UNITED STATES PATENT OFFICE

EDWARD L. HEFFRIN, OF WATERBURY, CONNECTICUT, ASSIGNOR TO THE SHOE HARDWARE COMPANY, OF WATERBURY, CONNECTICUT, A CORPORATION OF CONNECTICUT

CLOTHING BUCKLE

Application filed July 17, 1929. Serial No. 378,839.

This invention relates to clothing buckles of the type suitable for raincoats or other articles in which two edges or ends are to be detachably connected together.

5 The appearance of the ordinary type of buckle heretofore used on raincoats and similar apparel has not been entirely satisfactory, and, in an attempt to overcome the objection, some manufacturers have substituted snap fasteners for the buckles. But even though the appearance may be somewhat improved by snap fasteners, they have been for various reasons found unsuitable. It is therefore one object of this invention to provide 10 a clothing buckle of improved appearance and possessing at least the advantages of the ordinary clothing buckle and snap fastener while doing away with the objections to both.

15 Another object is to provide a buckle of substantially flat construction, thereby enhancing its appearance, and incorporating simplicity and low cost of manufacture.

Other objects and advantages will appear as the description proceeds.

20 Reference is to be had to the following specification and the accompanying drawing in which:

Fig. 1 is a plan view of the two buckle members embodying the invention;

25 Fig. 2 is a section on the line 2—2 of Fig. 1 indicating the preliminary position in coupling the two members together;

30 Fig. 3 is a section similar to Fig. 2 showing the two members snapped together; and

35 Fig. 4 is a plan view of the members coupled.

In the drawing, the numeral 1 indicates a substantially flat member, preferably of metal, and provided with perforations 2 2 whereby it may be attached to a garment or other article. The member 1 also has an elongated slot or eye 3, and a lip 4 formed on the edge of the body adjacent the eye 3. The other member of the buckle designated 5 is 45 also provided with perforations 6 and has a spring tongue 7 preferably struck from the body of the member 5 and extending across an aperture 11 therein, the tongue being slightly curved or inclined as indicated at 50 8 in Fig. 2. One edge of the member 5 is

provided with an extension which is bent to form a rounded hook 9 having an eye-engaging portion inclined toward the tongue 7. In the operation of coupling the two members together, they are placed at an incline to each other, as indicated in Fig. 2 with the lip 4 engaged in the aperture beneath the resilient tongue 7 of the member 5, the lip being preferably of a width such that it fits snugly between the edges 10 defining the aperture 11 55 opposite the sides of the tongue 7 and thereby guides or predetermines the position for bringing the two members together preliminary to snapping the hook 9 through the eye 3. During this operation it will be noted that the spring tongue 7 exerts pressure against the member 1 adjacent the lip 4, and that when the hook 9 has been fully inserted through the eye 3, as in Fig. 3, the tongue 7 60 coacts with the lip 4 to hold the hook 9 tightly in engagement with the near edge of the eye 3, thereby insuring a secure connection between the two members and holding them in parallelism.

It is obvious that the two members cannot 65 become disengaged except upon swinging one of the members at an angle or out of parallelism with the other so as to release the hook. This buckle provides an easy and quick way of connecting two edges of a garment or a belt or other article together, since it is necessary only to guide the lip 4 beneath the tongue 7, and then snap one member down against the other. It also presents a 70 neat appearance since the two buckles are substantially flat when coupled. The buckle 75 also has the advantage of inexpensiveness in that they are made in one piece each, and can be quickly stamped out by dies.

While the foregoing example embodies one 80 practical form of the invention, it is not intended as a limitation, since it is obvious that various modifications and alterations may suggest themselves to those skilled in the art without departing from the scope of the invention as defined in the appended claims.

Having thus described my invention, what I claim and desire to protect by Letters Patent is:

1. A clothing buckle comprising two sub-

100

- stantially flat members one of which is provided with an eye and a lip, the other member having an aperture and a spring tongue extending thereacross, and a hook carried by
5 said other member adapted to engage the first named member through said eye, the said lip being disposed in said aperture and engaging said tongue to releasably hold the hook engaged with the eye and dispose the
10 two members substantially in parallelism, said hook having a portion inclined toward said tongue and held in frictional engagement with the edge of said eye nearest said lip.
- 15 2. A clothing buckle comprising two substantially flat members, one of which is provided with an elongated eye and having a lip at the edge thereof adjacent said eye, the lip being disposed at an incline to the body
20 of said member, the other member being provided with an aperture and an outwardly directed spring tongue extending across the aperture, said lip being disposed in the aperture when the two members are connected
25 together, said other member also including a hook having a portion inclined toward said tongue and held in frictional engagement with the edge of said eye nearest said lip.

Signed at Waterbury, county of New Haven, State of Connecticut, this 12th day of July, 1929.

EDWARD L. HEFFRIN.
